UNITED STATES PATENT OFFICE

2,106,580

CIRCUIT BREAKER

Alfred J. Thomson, Detroit, Mich., assignor to
 Bulldog Electric Products Company, Detroit,
 Mich., a corporation of West Virginia

Original application March 6, 1933, Serial No.
 659,714. Divided and this application Jan-
 uary 9, 1936, Serial No. 58,438

9 Claims. (Cl. 200—116)

This application relates to circuit breakers and is a divisional of my prior application Serial No. 659,714, filed March 6, 1933.

The instant application discloses a circuit breaker having an actuating or operating mechanism to which is connected a contact and a handle. Normally the handle is positively connected to the operating mechanism to which is also positively connected the contact and movement of the handle positively causes movement of the mechanism and consequent movement of the contact for manual switching.

On overload operation, the positive connection between the handle and the mechanism is destroyed automatically so that overload movement of the actuating mechanism and consequent movement of the contact may take place without the necessity for causing or being accompanied by corresponding movement of the handle; in the instant breaker, there is a latch which normally positively connects the handle and the mechanism but which is automatically disengaged by overload release movement of the mechanism itself to disconnect the mechanism from the handle.

While in the ordinary sense it may be considered that the handle is normally connected to the mechanism positively and is completely disconnected therefrom automatically on overload release movement of the parts, it may be considered that for normal operation the handle is connected to the mechanism in such a manner that substantially no lost motion between the handle and the mechanism exists, the operation of the parts, however, being such that an overload release automatically causes a tremendous increase in the amount of lost motion between the handle and the mechanism so that the mechanism may move free of the handle, the handle not following or accompanying the mechanism due to the great lost motion that is automatically caused to exist between the handle and the mechanism following overload release.

The invention is embodied in a trippable or releasable latch between the operating handle of a circuit breaker and the quick acting mechanism of the same, to which mechanism is connected a contact. The mechanism per se and the general arrangement of the parts is substantially that disclosed in my prior application Serial No. 659,714.

For an understanding of the herein illustrated breaker which includes the operating mechanism of my prior application and embodies my instant invention, reference should be had to the follow-

ing description and the accompanying drawings, in which,

Figs. 1-3a are plan, end, elevation, and dia-
 grammatic views of a breaker, shown in on position;

Figs. 4 and 5 are elevation and end views of a
 group of details of the mechanism thereof, in on
 position;

Figs. 6 and 7 are elevation views of the breaker,
 in off and overload off positions, respectively;

Fig. 8 is an elevation view, like Fig. 4, but with
 the parts shown in overload off position.

In the drawings there is shown a breaker hav-
 ing the operating mechanism of my prior ap-
 plication and having a handle and a contact con-
 nected thereto. Normally connecting the handle
 and the mechanism is a latch; this latch is auto-
 matically released on overload release movement
 of the mechanism itself to destroy the normal
 operative connection between the handle and the
 mechanism, whereupon the mechanism and its
 contact may move free of the handle on overload
 release.

As stated above, the breaker operating mecha-
 nism in general resembles that of my prior ap-
 plication Serial No. 659,714 and has many parts
 which are similar to the identically numbered
 parts of that breaker. For example, both break-
 ers have a base 10, a warping element 14, a front
 plate 21, an operating link 24, a spring 27 there-
 on, between pin 28 and a link 29 connected at
 31 to a pawl 32 pivoted at 33, the pawl having an
 end 35 for engagement by tongue 36 of the warp-
 ing element. The left end 37 of link 24 is con-
 nected to the drum-like crank 38 by pin 39 riding
 in slot 41 of the crank, the latter having a handle
 42, and being supported on shaft 43 connecting
 the front plate 21 to the back plate 43a and hav-
 ing pin A riding in slot B in front plate 21.
 The crank further has a lug 44 to engage a
 stop 45 on the pawl, and there is also provided
 a pawl stop ledge 47 on a pawl stop 48.

In addition to the foregoing parts, the breaker
 of this case is provided with certain novel de-
 tails, now to be described.

On base 10 are contacts 111 adapted to be en-
 gaged by the bridging contact 112 on one end of
 contact arm 113, the contacts 111 being con-
 nected to the load and to the warping element
 14, respectively.

The other end of arm 113 is enlarged and is dis-
 posed within the drum-like bell crank 38 (Fig. 4)
 and is also journaled on cross shaft 43. The arm
 may be latched to the bell crank, so as to move
 therewith by a plate 115 through which passes 55

pin 39 on the end of link 24, the pin riding in a slot 117 of the contact arm aligned with slot 41 of the crank, the plate having an edge notch 118 in which may be disposed a latch 119, journaled by means of its lugs 120 riding in holes 121 of the drum-like crank, and held down in notch 118 by a tension spring 122 connecting the latch and a pin 123 on the contact arm 113.

The parts just described may be operated as a simple quick make and break switch as follows:

When handle 42 is moved to the right from on position, Figs. 3, 3a, and 4, left end 39 of link 24 is moved up and to the left compressing spring 27. While pin 39 is riding in slot 117 of switch arm 113 and tensioning spring 122, switch arm 113 is being held by frictional engagement of the stationary contacts 111 with movable contact 112.

After link 24 gets overcenter 43, spring 27 acts to complete the clockwise movement of left end 39 and handle 42. Switch arm 113, through the influence of spring 27 assisted by spring 122, effects a quick break of the movable contact 112 from the stationary contacts 111.

Reverse movement of handle 42 from off position, Fig. 6, causes left end 39 of link 24 to move counterclockwise and to the left, tensioning spring 27 and also moving with it, contact arm 113. After link 24 moves overcenter 43, spring 27 re-acts to cause quick make of the movable contact 112 to the stationary contacts 111. The positive connection through the medium of the latch 119, the plate 115, and the pin 39 insures positive make and break.

To the foregoing are added parts for moving the contact arm on overload trip independently of, and without requiring movement of, the handle 42, and these will now be described. In the crank 38 there is disposed a slidable plate 126 guided by, and whose slot 127 receives, the cross shaft 43. This plate has an extension 128 at one end passing through a slot 129 of the drum crank 38 and its other end is positioned to engage the latch 119.

The overload trip operation of these parts is as follows: When the element 14 warps to the right, it releases pawl 32; the latter is then snapped upwardly by spring 27. The link 24 also moves with pawl 32 about pin 39 as a fulcrum. The extension 128 of plate 126 is engaged by the extension 130 of pawl 32 and is forced upward to release latch 119 from notch 118, and allowing pin 39 to rotate clockwise under the combined influence of springs 122 and 27 and through the movement of switch arm 113, forcing movable contact 112 away from stationary contacts 111 to effect a quick break of the circuit. Arm 113 moves independently of crank 38, for a trip free action, by virtue of the fact that pin 39 can ride freely in slot 41 of the crank. Movement of crank 38 is limited by the riding of its pin A in the slot B of the front plate 21. The characteristic that arm 113 can move independently of crank 38, so that arm 113 can move to break the circuit even though the crank 38 is held manually in on position, places the breaker in the trip free class.

Excess movement of pawl 32 is prevented, not only by stop ledge 47, but also by the engagement of pawl extension 130 with an extension 131 formed on contact arm 113 and projecting through slot 129.

For resetting the parts to normal position, handle 42 is moved to the right to move pawl 32 down, lug 44 pressing against shoulder 45 of pawl 32, until end 35 latches under projection 36 on

overload element 14. During this movement, pin 39 rides free in slot 41. Movement of the handle 42 also rotates latch 119 in crank 38 until it aligns with slot 118 in member 115, whereupon the spring 122 pulls latch 119 in the slot 118, again latching member 115, to crank member 38. Also, the resetting movement of pawl 32 frees end 128, allowing latch 119 to engage slot 118.

Contact arm 113 does not move out of the off position, being held in that position through the medium of link 24 and pin 39 together with shoulder 53 of link 24 pressing against the lug 52 of link 29. The reset action therefore places all the parts in off position.

It will be observed that normally the handle 42 is positively connected to the operating mechanism, with little or no lost motion between the parts through the latch 119. On overload release movement of the parts, however, the handle is disconnected from the operating mechanism so that there is great lost motion between the handle and the mechanism and so that the mechanism may move free of the handle, and such disconnection is accomplished by raising of latch 119 out of the notch 118 in member 115 of the operating mechanism; this is accomplished by the engagement of the latch controlling part 128 by the pawl extension 130, which pawl extension moves up on overload release of the parts to strike latch-control member 128 and raise latch 119 out of the notch 118 in member 115.

I claim:

1. In a circuit controller, a contact, quick acting circuit opening and closing mechanism positively connected thereto and so constructed as to have a normal tendency to move the contact and thus open the circuit when permitted so to do, holding means for the mechanism and arranged to release it on overload and permit it to operate for circuit opening, a handle for operating the mechanism for circuit opening or closing even when the mechanism is held by the holding means, and rigid but releasable means normally positively connecting the handle and the mechanism and automatically released by overload release movement of the holding means for disconnecting the handle and the mechanism, whereby the mechanism may operate the contact for circuit opening free of the handle and even if the latter be held, the holding means for the mechanism being separate and independent of the rigid but releasable means for connecting the mechanism and the handle and also being remote from such rigid and releasable means.

2. In a circuit controller, a contact, quick acting circuit opening and closing mechanism positively connected thereto and so constructed as to have a normal tendency to move the contact and thus open the circuit when permitted so to do, holding means for the mechanism and arranged to release it on overload and permit it to operate for circuit opening, a handle for operating the mechanism for circuit opening or closing even when the mechanism is held by the holding means, and rigid but releasable means normally positively connecting the handle and the mechanism and automatically released by the mechanism itself following a movement thereof responsive to overload release movement of the holding means for disconnecting the handle and the mechanism, whereby the mechanism may operate the contact for circuit opening free of the handle and even if the latter be held, the holding means for the mechanism being separate and independent of the rigid but releasable means for

connecting the mechanism and the handle and also being remote from such rigid and releasable means.

3. In a circuit controller, a contact, quick acting circuit opening and closing mechanism positively connected thereto and so constructed as to have a normal tendency to move the contact and thus open the circuit when permitted so to do, holding means for the mechanism and arranged to release it on overload and permit it to operate for circuit opening, a handle for operating the mechanism for circuit opening or closing even when the mechanism is held by the holding means, the handle and the mechanism being normally positively connected through rigid but releasable connecting means so that complete movement of the handle necessarily causes circuit opening movement of the mechanism, overload release of the holding means automatically releasing such releasable connection so that circuit opening movement of the mechanism responsive to overload release can take place free of the handle, the holding means for the mechanism being separate and independent of the rigid but releasable means for connecting the mechanism and the handle and also being remote from such rigid and releasable means.

4. In a circuit controller, a contact, quick acting circuit opening and closing mechanism positively connected thereto and so constructed as to have a normal tendency to move the contact and thus open the circuit when permitted so to do, holding means for the mechanism and arranged to release it on overload and permit it to operate for circuit opening, a handle for operating the mechanism for circuit opening or closing even when the mechanism is held by the holding means, the handle and the mechanism being normally positively connected through rigid but releasable connecting means so that complete movement of the handle necessarily causes circuit opening movement of the mechanism, overload release of the holding means automatically causing the mechanism itself to operate for releasing such releasable connection so that circuit opening movement of the mechanism responsive to overload release can take place free of the handle, the holding means for the mechanism being separate and independent of the rigid but releasable means for connecting the mechanism and the handle and also being remote from such rigid and releasable means.

5. In a circuit controller, a contact, quick acting circuit opening and closing mechanism positively connected thereto and so constructed as to have a normal tendency to move the contact and thus open the circuit when permitted so to do, holding means for the mechanism and arranged to release it on overload and permit it to operate for circuit opening, a handle for operating the mechanism for circuit opening or closing even when the mechanism is held by the holding means, the handle and the mechanism being normally positively connected through rigid but releasable connecting means so that complete movement of the handle necessarily causes circuit opening movement of the mechanism, overload release of the holding means automatically releasing such releasable connection so that circuit opening movement of the mechanism responsive to overload release can take place free of the handle, the handle and the mechanism being normally positively connected through rigid lost motion means so that partial movement of

the handle does not open the circuit through the mechanism but complete movement of the handle does open the circuit through the mechanism, overload release of the holding means automatically and considerably increasing such lost motion so that circuit opening through movement of the mechanism responsive to overload release can take place even though the handle be held.

6. In a circuit controller, a contact, quick acting circuit opening and closing mechanism positively connected thereto and so constructed as to have a normal tendency to move the contact and thus open the circuit when permitted so to do, holding means for the mechanism and arranged to release it on overload and permit it to operate for circuit opening, a handle for operating the mechanism for circuit opening or closing even when the mechanism is held by the holding means, the handle and the mechanism being normally positively connected through rigid but releasable connecting means so that complete movement of the handle necessarily causes circuit opening movement of the mechanism, overload release of the holding means automatically causing the mechanism itself to operate for releasing such releasable connection so that circuit opening movement of the mechanism responsive to overload release can take place free of the handle, the handle and the mechanism being normally positively connected through rigid lost motion means so that partial movement of the handle does not open the circuit through the mechanism but complete movement of the handle does open the circuit through the mechanism, overload release of the holding means acting through the mechanism itself for automatically and considerably increasing such lost motion so that circuit opening through movement of the mechanism responsive to overload release can take place even though the handle be held.

7. In a circuit breaker, a handle, an operating mechanism, an overload release latch for said mechanism and arranged to hold said mechanism normally and to move in response to circuit conditions to free and release said mechanism, the latter being constructed to have an inherent tendency to move out of latch-held position, which movement is inhibited normally by the holding thereof by the overload release latch, means operatively connecting said mechanism to said handle, such means comprising a releasable latch, separate and independent of the overload release latch, and arranged to normally latch the mechanism to the handle and to be released so as to release the handle from the mechanism, in response to a movement of the mechanism, in turn responsive to a release of the mechanism by overload release movement of the overload release latch, whereby the mechanism can move free of the handle after the mechanism has caused the handle latch to be released.

8. A construction of the character of claim 5 wherein the holding means for the mechanism is separate and independent of the rigid but releasable means for connecting the mechanism and the handle and also is remote from such rigid and releasable means.

9. A construction of the character of claim 6 wherein the holding means for the mechanism is separate and independent of the rigid but releasable means for connecting the mechanism and the handle and also is remote from such rigid and releasable means.

ALFRED J. THOMSON.
